(57) **CLAIM**

The ornamental design for a combined cable management device with suction cup attachment end and belt clip, as shown and described.

DESCRIPTION

FIG. 1 is a perspective view of my new design for a combined cable management device with suction cup attachment end and belt clip with the belt clip portion removed for clarity of illustration;

FIG. 2 is an exploded view of the complete design;

FIG. 3 is a perspective view thereof with the belt clip portion joined with the cable management portion;

FIG. 4 is a front plan view of the cable management portion;

FIG. 5 is a rear plan view of the cable management portion;

FIG. 6 is a perspective view of the rear of the cable management portion;

FIG. 7 is a right side view of the cable management portion;

FIG. 8 is a left side view of the cable management portion;

FIG. 9 is a top plan view of the cable management portion;

FIG. 10 is a bottom plan view of the cable management portion;

FIG. 11 is a perspective view of the front of the belt clip portion;

FIG. 12 is a front plan view of the belt clip portion;

FIG. 13 is a perspective view of the rear of the belt clip portion;

FIG. 14 is a rear plan view of the belt clip portion;

FIG. 15 is a right side view of the belt clip portion, the left side view being a mirror image thereof;

FIG. 16 is a top plan view of the belt clip portion; and,

FIG. 17 is a bottom plan view of the belt clip portion.
